CLAIM

The ornamental design for a combined rotatable confection and handle, as shown and described.

DESCRIPTION

FIG. 1 is an elevational view of a combined rotatable confection and handle showing my new design, the opposite side being the same in appearance;

FIG. 2 is an elevational view looking from the left of FIG. 1, the opposite side being the same in appearance;

FIG. 3 is a top plan view; and

FIG. 4 is a bottom plan view thereof.

The central, unshaded areas are solid.
